UNITED STATES PATENT OFFICE.

ERNEST TURNER, OF ALEXANDER CITY, ALABAMA.

SUBSOILING DEVICE.

1,246,501.

Specification of Letters Patent. Patented Nov. 13, 1917.

Application filed December 6, 1916. Serial No. 135,439.

To all whom it may concern:

Be it known that I, ERNEST TURNER, a citizen of the United States, and a resident of Alexander City, in the county of Tallapoosa and State of Alabama, have invented 5 a new and Improved Subsoiling Device, of which the following is a full, clear, and exact description.

The general objects of my invention are 10 to reduce the cost incident to subsoiling with explosive materials by the present methods; to minimize the dangers of accidental explosion which are incident to present methods; and to increase the effectiveness of the 15 explosive force on the soil.

In carrying out my invention a tube is provided, adapted to be inserted in the ground to be blasted and adapted to constitute at its forward end a container for 20 blasting powder. A plunger is slidably fitted in the tube in the rear of the explosive charge, and a percussion cap, a match head, or the like, may be employed to cause ignition of the charge under the impact of the 25 plunger. In connection with the plunger a sliding weight is employed thereon in the rear of the tube, the weight being retained in an elevated position on the plunger by a removable pin which is adapted to be withdrawn 30 by a pull cord extending to a safe distance. On the plunger a collar is provided to receive the blow of the weight when the latter is released so that the blow will give a forward impulse to the plunger to 35 produce the explosion.

The invention will be particularly explained in the specific description following.

Reference is to be had to the accompanying drawings forming a part of this specification in which similar reference characters indicate corresponding parts in all the views.

Figure 1 is a partly sectional side elevation of a subsoiling device constructed in accordance with my invention, showing the 45 position of the parts before releasing the weight;

Fig. 2 is a similar view showing the position of the parts after the explosion;

Fig. 3 is a side elevation showing a 50 slightly different form of the device;

Fig. 4 is a fragmentary longitudinal section of the forward end of the tube shown in Fig. 3;

Fig. 5 is a cross section on the line 5—5, 55 Fig. 4;

Fig. 6 is a vertical section on a reduced

scale of the tube in another form with associated driving elements;

Fig. 7 is a view similar to Fig. 6 showing the tube in the driven position and containing 60 a charge of powder, the driving tool being removed.

In constructing a practical embodiment of my invention, the tube to contain the explosive charge may be of a form to be inserted in a previously made hole in the ground; or given a form to be driven into the ground thereby cutting its own way in the soil, or a driving plunger and head may be provided whereby to drive the tube. 70

Referring more particularly to Figs. 1 and 2 the tube 10 has a throughbore 11. At the forward end the tube is adapted to receive a charge 12 of blasting powder or the like and a percussion cap 13 or equivalent percussion element to ignite the charge. My improved device makes it possible to effectively subsoil with blasting powder, thereby avoiding the dangers incident to dynamiting and also materially reducing the 80 cost of the work.

Slidably fitted in the tube 10, in the rear of the explosive charge is a plunger 14 which may be restrained against forward movement in the tube by a removable pin 85 15 which is receivable in a transverse hole 16 in the plunger and adapted to rest on the rear end of the tube 10.

In order to give a forward impulse to the plunger 14, I provide a sliding weight 17 thereon. The weight is sustained in the elevated position as shown in Fig. 1 by a pin 18 which is passed through a transverse hole 19 in the plunger. To the pin 18 is connected one end of a pull cord 20 which 90 in practice will be of a length to extend a safe distance. On the plunger 14 a collar 21 or equivalent member is formed or secured to receive the blow of the hammer 17. 95

In practice, with the form shown in Figs. 100 1 and 2, a hole having been formed in the ground, the tube 10 is inserted in the hole and a charge of black powder is poured into the tube, the percussion cap or a match head is then dropped through the tube onto the 105 powder, the plunger 14 is now inserted in the tube in the rear of the explosive charge, and the pin 15 inserted to prevent an accidental explosion. When it is desired to effect the explosion, the pin 15 is removed 110 and the plunger gently lowered onto the percussion cap, the operator now may pull

the string 20 at a safe distance from the device, thereby withdrawing the pin 18 and permitting the weight 17 to drop and engage the collar 21, thereby causing the plunger 5 to explode the percussion cap and ignite the charge. A powerful result is obtained since the explosion of the powder occurs under the pressure exerted by the blow, the full force of the explosion being effective 10 on the soil through the lower open end of the tube.

In the form shown in Fig. 3, the plunger and its appurtenances are the same in all respects with the form shown in Figs. 1 and 15 2, the tube 10^a, however, corresponding with the tube 10, has a pointed lower end 22 whereby the tube may be readily driven into the ground, thereby boring its own hole as the tube advances. As the pointed end is 20 closed, the lateral openings 23 are formed in the tube near the lower end and disposed at different angles, whereby the explosion of the powder 12^a will be effective in various directions against the soil.

25 In Figs. 6 and 7, the tube designated 10^b has an enlarged head 10^c, and the lower end of the tube is tapered exteriorly. The tube in this form is adapted to be driven by a driving tool comprising a plunger 24 having a tapered lower end 24^a adapted to project through the lower end of the tube. Said plunger has a head 25 which is preferably removable that it may be renewed without damage. In practice the plunger 24 is 30 placed in the tube 10^b with the head resting on the enlarged head 10^c of the tube. The tube and plunger are then driven by blows of a maul or the like delivered against the head 25. When the tube is driven the 35 plunger is removed and a charge of powder inserted in the tube and tapered hole formed by the plunger at the lower end of the tube, whereby the plunger 14 may be employed to explode the said powder in the manner described.

Having thus described my invention I claim as new, and desire to secure by Letters Patent:—

1. A subsoiling device including a tube 50 adapted to form at its front portion a con-

tainer for an explosive charge and percussion element and be inserted in the ground to be blasted, said tube having an outlet at said front end for the explosive to be effective on the soil, a plunger fitting said tube 55 and adapted to move forward toward the charge-receiving front end under the force of a blow for exploding the charge by impacting the plunger against the percussion element, removable means to hold the plunger against forward movement in the tube, a weight slideable on the plunger in the rear of the tube, said rod having a member thereof rearward of the tube to receive the impact of the weight, said plunger having a 60 member thereon in the rear of the tube to receive the blow of the hammer and having a transverse pin hole near the rear end of the tube, and a pin fitting said pin hole and adapted to be withdrawn by a pull thereon 65 to permit the weight to drop against the member on the plunger.

2. A subsoiling device including a tube adapted to form at its front portion a container for an explosive charge and a percussion element and be inserted in the ground to be blasted, a plunger slidably fitting said tube at the rear end and of a length to project rearwardly therefrom, a sliding weight on the plunger in the rear of the tube, and means to releasably sustain the weight in position near the rear end of the plunger, the said plunger having a member adapted to receive the blow of the weight 75 when the latter is released.

3. A subsoiling device including a tube adapted to receive an explosive charge to be exploded as a result of impact, said tube being adapted to be inserted in the ground to be blasted, a plunger slidably fitting said tube at the rear end and of a length to project beyond the rear of the tube, a sliding weight on the plunger rearward of the tube, and means to releasably sustain the weight 80 on the plunger in the rear of the tube, said plunger having a member thereon between 85 the weight and the tube to receive the blow of the weight.

ERNEST TURNER.
